UNITED STATES PATENT OFFICE.

JOHN C. CRAMER, OF DAYTON, OHIO.

DESIGN FOR A SMOKER'S STAND.

Application filed April 13, 1927. Serial No. 21,578. Term of patent 3½ years.

To all whom it may concern:

Be it known that I, JOHN C. CRAMER, a citizen of the United States, residing at Dayton, in the county of Montgomery and State of Ohio, have invented a new, original, and ornamental Design for a Smoker's Stand, of which the following is a specification, reference being had therein to the accompanying drawing.

In the drawing:

Fig. 1 is a front elevation of the stand showing my new design; and Fig. 2 is a side elevation thereof.

I claim:

The ornamental design for a smoker's stand substantially as shown.

In testimony whereof, I affix my signature.

JOHN C. CRAMER.
